assignments, to George M. Schroeder and Al-
bert A. Schroeder, Kenosha, Wis.

Application April 1, 1948, Serial No. 18,338

4 Claims. (Cl. 315—336)

1

This application is a continuation-in-part of our copending application, Serial No. 637,972, filed December 29, 1945, in "Luminous Tube Apparatus", now abandoned.

This invention relates to luminous tube apparatus of the type wherein luminescent electric discharges are produced in gas-filled tubes.

Luminous tube apparatus of the aforesaid character may take the form of sealed glass tubes filled with neon, argon-mercury vapor, or other gases, and operating electrical connections are afforded by electrodes disposed within and adjacent the opposite ends of the tube. In the more common uses of such luminous tubes, as for example, in advertising or some types of illumination, these tubes are of the cold-cathode type.

In luminous tubes of the aforesaid character it has long been recognized that the effectiveness and the useful life of the tubes has been adversely affected by the phenomenon of sputtering which produces a metallic deposit of the electrode metal on the inner tube surface adjacent to the electrodes. This sputtering of metallic particles onto the inner surface of the glass tubing eventually forms a metallic deposit in the form of a dark or black discoloration on the inner surface of the glass tubing and causes an arcing of the current from the metallic electrode to the thus metal-coated inner surface of the tube which, as a result thereof, becomes hot and eventually burns out. The formation of such metallic deposit also reduces the luminosity of the tube, and results in uneven heating and consequent cracking of the glass wall of the tube. This sputtering is a familiar phenomenon observed in red or rose-colored neon luminous tube signs and in white, blue, green or gold colored argon-mercury vapor signs.

An object of the present invention, therefore, is to provide a new and improved luminous tube apparatus which in use will overcome the foregoing and other objections to prior art luminous tube apparatus. Another and related object of the present invention is to reduce and substantially eliminate objectionable sputtering in luminous tube apparatus of the aforesaid character.

In luminescent tube apparatus of the aforesaid character it is recognized that relatively large area electrodes are desirable in order to minimize the cathode drop and facilitate radiant dissipation of the heat generated as an incident to the operation of the tube, and further objects of the invention are to enable such large area electrodes to be used without objectionable sputtering, and to prevent objectionable sputtering at

2

the open ends of elongated cup-shaped collector electrodes in such apparatus.

In affording collector electrodes in such luminous tubes so that such electrodes will have sufficient surface area to afford adequate radiant dissipation and to minimize the cathode drop, it is customary to utilize elongated cup-like or tube-like electrodes having the open ends thereof facing toward each other, or longitudinally inwardly with respect to the ends of the tubes, and with such electrodes it is found that the objectionable sputtering phenomenon arises primarily from the ionic bombardment of the walls of the electrodes at or closely adjacent the open ends thereof. It is therefore another important object of the present invention to confine such ionic bombardment of the collector electrodes to those internal surfaces thereof that are spaced substantially from the open ends of such electrodes. Other and related objects of the present invention are to enable the electrical discharge to be confined or focused as such discharge approaches the open end of a collector electrode; to enable such focusing effect to direct the electrical discharge into the open end of the collector electrode in spaced relation to the side walls thereof; and to enable the bombardment to be confined largely to the bottom or closed end wall of the electrode.

Other and further objects of the present invention will be apparent from the following description and claims and are illustrated in the accompanying drawing which, by way of illustration, shows preferred embodiments and the principles thereof and what we now consider to be the best mode in which we have contemplated applying those principles. Other embodiments of the invention embodying the same or equivalent principles may be used and structural changes may be made as desired by those skilled in the art without departing from the present invention and the purview of the appended claims.

In the drawings:

Fig. 1 is a fragmentary central vertical sectional view of a luminous tube apparatus illustrating a typical embodiment of the invention;

Fig. 2 is a sectional plan view on line 2—2 in Fig. 1;

Fig. 3 is a transverse vertical sectional view on line 3—3 in Fig. 2;

Fig. 4 is a fragmentary central view partly in section and partly in elevation illustrating a modified construction and form of the invention;

Fig. 5 is a central vertical sectional view of the form of the invention shown in Fig. 4;

Fig. 6 is a fragmentary view, partly in section and partly in elevation, illustrating a preferred form of feed back conductor or wire and connector therefor which is embodied in the form of the invention illustrated in Figs. 4 and 5;

Fig. 7 is an enlarged transverse sectional view on line 7—7 in Fig. 6;

Fig. 8 is a transverse vertical sectional view 10 on line 8—8 in Fig. 5; and

Fig. 9 is an enlarged fragmentary sectional view of the parts shown in Fig. 8.

A typical embodiment of the present invention is illustrated in the drawing wherein it is shown as being embodied in a positive column luminous tube apparatus having an outer glass tube 10 which may be formed of any suitable quality of glass such, for example, as lead glass, and which may be filled with any suitable ionizable gas or gas-vapor mixture such, for example, as neon gas for rose or red-colored luminous signs and the like and argon-mercury vapor for use in white, green, blue or gold-colored luminous signs and the like.

The outer glass tube 10 is provided at its ends, only one of which is shown, with an integral sealing nipple 11, through which a central bore or passage 12 extends, and a lead wire 13 is extended through and hermetically sealed in the bore or passage 12 of the nipple 11.

In the construction of the form of the invention shown in Figs. 1 to 3, inclusive, we provide an electrically non-conductive inner electrode-supporting member 14 which may be made of any suitable electrically non-conductive ceramic or glass material such, for example, as "Pyrex" glass, and this electrode-supporting member 14 includes a portion 15 of relatively restricted diameter and a portion 16 of larger diameter. The inner glass shell or electrode-supporting member 14 includes an integral nipple 17 which is provided with a central bore 18 through which a portion 19 of the metallic lead wire or rod 13 is extended, Figs. 1 and 2.

The form of the new luminous tube apparatus which is illustrated in Figs. 1 to 3, inclusive, includes a substantially tubular metallic electrode 20 which may be made of any suitable metal such, for example, as a nickel-steel alloy. The major portion or main extent of the tubular metallic electrode 20 is disposed within and in close fitting relationship with the relatively narrow or restricted portion 15 of the inner glass shell or electrode-supporting member 14 and the inner end portion of the metallic lead-in wire or conductor member 13 is extended into and welded or soldered to the adjacent closed end portion of the metallic electrode, as at 21, Fig. 2. The metallic electrode 20 also includes a portion 22 which projects into the enlarged portion 16 of the inner glass shell or electrode-supporting member 14 in spaced relationship with and relative to the inner surface of the enlarged portion 16 of the electrode-supporting member 14.

In the practice of the form of the invention shown in Figs. 1 to 3, inclusive, we provide an electrically conductive element or substantially cylindrical shield electrode 23 in the form of a coating over substantially the entire inner surface of the enlarged portion 16 of the glass insert or electrode-supporting member 14, and the outer end wall or edge thereof. This electrode 23 is preferably of low resistance electrically conductive initially liquid silver coating, or

other suitable low electrical resistance metal coating. For the purpose of affording a stabilized biasing potential on the electrode 23 with respect to the electrode 20, an electrical path is preferably afforded between the lead 13 and the electrode 23. In the form illustrated such path is afforded within the tube 20, and to accomplish this we extend or continue a relatively narrow band or strip 24 of this low resistance silver or like metallic coating over the outer surface of the enlarged portion 16 of the inner glass supporting member 14. This electrically conductive strip 24 is thus continuous at one end with the electrode 23 on the inner surface of the enlarged portion 16 of the electrode-supporting member 14, and is interrupted between its ends by a biasing impedance which, as shown herein, takes the form of a relatively short section or block 25 of liquid platinum coating material which is arranged upon the outer surface of the relatively small portion 15 of the inner glass electrode-supporting member 14 as a relatively thin coating which by reason of its small cross-sectional area affords a high resistance electrical path. This biasing resistor may have a resistance of from one hundred to two hundred ohms. The electrical path thus afforded also includes a further section 26 extended from the other side of the impedance or resistance element 25, and formed of the low resistance electrically conductive liquid silver coating which is arranged on the outer surface of the reduced portion 15 of the glass insert or electrode-supporting member 14. As shown in Figs. 1 and 2, the section 26 of low resistance electrically conductive liquid silver coating is extended down over the nipple 17 of the glass insert of electrode-supporting member 14 and is disposed in electrical contact with the lead wire 13.

In the use of the form of the new luminous tube apparatus which is illustrated in Figs. 1 to 3, inclusive, the luminous glass tube 16 may be formed in any suitable shape and size and the lead wires 13 may be connected in the conventional manner across any suitable source of electric current as, for example, 18 to 60 milliamperes at 15,000 volts in the case of neon luminous tube signs and, in the case of argon-mercury vapor luminous tube signs, about 120 milliamperes at 7500 volts.

Luminous tube apparatus of the character thus afforded is of course adapted for use in direct current circuits, or in alternating current circuits where there is a reversal of the polarity of the operating voltage twice in each cycle of the alternating current. When the luminous tube apparatus disclosed in Figs. 1 to 3 is thus utilized, it has been found that the sputtering phenomenon is so controlled and governed that its presence or the formation of a metallic deposit on the tube cannot be noticed to any objectionable extent, and this improved operation has been found to be due to a focusing action that is attained by the electrode 23. Thus it has been determined that at the cathode, the positive column extends at least partially into the space within the control electrode 23, so that the Faraday dark space is actually disposed substantially at the lip or open end of the electrode 20. Within the control electrode 23, however, there has been found to be a positive space charge on the inner surface of the electrode 23 which reduces the diameter of that portion of the positive column, hence the positive ions from the negative glow area bombard the cathode or collector electrode

20 in such a way as to pass into the open end of the collector electrode 20. Thus the ions as well as the electrons must strike the internal surface of the collector electrode 20 at points spaced inwardly a substantial distance from the open 5 end of the electrode 20, and as a result, any displacement or sputtering of electrode metal is confined to the space within the electrode so that such displaced electrode metal does not strike or become deposited on the inner surface of the tube. Another factor in this regard is the control of secondary emission, for the presence of the control electrode 23 with a charge thereon that is relatively negative with respect to the plasma and with respect to the cathode tends to repel any negative electrons that may be set in motion by the ionic bombardment of the collector electrode that is functioning as the cathode. Similarly at the electrode 20 that is serving as the anode, the charge on the related control electrode 23 is more negative than such electrode 20, and there is a positive space charge thereon so that the positive column is reduced in cross section and the electronic bombardment is directed to the inner walls of the cup. The fact that such bombardment is in both instances confined to the inner surfaces of the electrode 20 remote from the open end serves of course to reduce the possibility that the electrons resulting from such bombardment will reach the glass tube 10 adjacent this open end of the electrode, and the control electrode 23 serves as a further protection in that the relatively negative field afforded about the open end of the electrode 20 has a suppressing action tending to prevent continued outward travel of such secondary electrons or secondary emission. Hence, the usual gathering of such secondarily emitted electrons on the inner surface of the tube 10 adjacent the open end of an electrode 20 is avoided, and a 10 concentration of negative electrons on the tube surface is not available for combination with positive ions to form an inner metal coating on the tube as is usually experienced in conventional luminous tubes of this class.

The controlling action that is thus exerted by the electrode 23 on the ionic bombardment of the electrodes 20 has been found to be due fundamentally to its relative location and to its electrical relationship which in operation causes 50 such electrode 23 to assume an effective biasing potential. This action is of course most important at the cathode, for it is there that the sputtering phenomenon has been most troublesome. The connection of the control electrode 23 to the electrode 20 through a biasing impedance such as the resistance 25 serves of course to impart the desired biasing potential relationship. The bias potential between the control electrode and the collector electrode should be approximately 60 25 volts.

In practice it has been found that the inner surface of the control electrode 23 has a dark sheath appearing thereon, and this is taken as an indication of a positive space charge which produces the focusing effect that is attained in the present structure. Moreover, by comparison of the structure with different connections or relationships between the control electrode 23 and the main electrode 20, further weight is given to the conclusion that the electrode 23 has an advantageous control action. Thus, in experiments, when the control electrode and the main electrode were directly connected so as to be at the same potential, practically all of the current 70 75

flow was found to be through the control electrode, but when a biasing connection was placed between these electrodes the dark sheath appeared on the inner surface of the control electrode and practically the entire current flow was handled by the main electrode, rather than through the control electrode.

A modified form of the invention is illustrated in Figs. 4 to 9, inclusive, and those parts embodied in this form of the invention which are similar to corresponding parts in the form of the invention shown in Figs. 1 to 3, inclusive, have been given similar reference numerals followed by the distinguishing reference character "a." The description of such parts will be apparent from the description of corresponding parts in the form of the invention shown in Figs. 1 to 3, inclusive, and hence need not be repeated.

In the form of the invention shown in Figs. 4 20 to 9, inclusive, we mount an electrode 23a in any suitable manner, as by a frictional fit, in the interior of the enlarged portion 16a of the inner glass shell or electrode-supporting member 14a. This electrode 23a is afforded by a substantially cylindrical shield or electrically conductive element 26 of relatively thin steel and which is provided on its outer and inner surfaces with coatings 27 and 28, respectively, of electrically conductive and substantially chemically pure or so-called soft iron.

In place of the biasing connection provided by the low resistance silver coating 23 and the silver stripe or band 24-26 and interposed high resistance platinum block 25, which are embodied in the form of the invention shown in Figs. 1 to 3, inclusive, we provide in the form of the invention shown in Figs. 4 to 9, inclusive, and in association with the electrode 23a, a biasing connection indicated generally at 29. This biasing connection 29 is afforded by a wire having a steel core or body 30 having an outer coating 31 of substantially chemically pure soft iron, Fig. 9.

As shown in Figs. 4 and 5, the wire 29 extends across the outer surface of the electrode supporting member 14a and one end portion 32 of the wire 29 is bent around one end wall of the enlarged portion 16a of the inner glass electrode-supporting member 14a and into electrical contact with the inner soft iron coating 28 on the steel shell or cylinder 26.

The wire 29 comprises two sections 29a and 29b, the section 29a including the end portion 32 just described, and the section 29b including a substantially cylindrical connecting portion 33 which is bent around and into electrical contact with the connecting lead 13a adjacent the outer end of the sealing nipple 17a on the reduced end portion 15a of the inner glass electrode-supporting member 14a, Figs. 4 and 5.

The wire 29 also includes an intermediate connector or wire 29c which is disposed between the end sections 29a and 29b of the wire 29.

As best shown in Fig. 6, each of the end sections 29a and 29b of the wire 29 has a formed or flattened clamping end portion or jaw 33 formed therein and integrally therewith. Each of these clamping jaws 33 includes a pair of clamping arms or ears 34 and 35 which are bent around and into electrically tight contact or engagement with an end portion of the intermediate wire section 29c and, as shown in Fig. 7, each of the clamping end portions 33 is composed of an inner steel core or body 36 and an outer soft iron coating 37 thereon. Thus it will be noted that the steel core or body 36 of each clamping end

portion 33 is an integral shaped or formed continuation of the steel core or body 30 of one of the end sections 29a or 29b of the wire 29 and that the soft iron coating 31 on each of the clamping jaws 33 is an integral shaped or formed continuation of the soft iron coating 31 on the body 36 of the steel wire 29.

In the construction of the form of the invention shown in Figs. 4 to 9, inclusive, the electrode 23a that is afforded by the iron coated steel shell or cylinder 26—27—28 may be frictionally or otherwise fitted into the enlarged portion 16a of the inner glass electrode-supporting member 14a and the section 29a of the wire arranged over the outer surface of the enlarged portion 16a and over the outer surface of the reduced end portion 15a of the inner glass shell or electrode-supporting member 14a with the end portion 32 thereof bent around the end wall of the enlarged portion 16a of the inner glass shell 14a and soldered or otherwise secured in electrically tight contact to the soft iron inner coating 28 on the steel shell or cylinder 26. Similarly, the section 29b of the wire 29 is laid over the outer surface of the reduced end portion 15a of the inner glass shell or electrode-supporting member 14a with the end portion 32 of the wire section 29b bent around and soldered or otherwise electrically connected to the lead 13a, as shown in Figs. 4 and 5.

The end portions of the intermediate wire section 29c may then be inserted in the substantially cylindrical clamping portions 33 of the wire sections 29b and 29c. The ears or clamping portions 34 and 35 of the clamping members 33 may then be clamped, by means of any suitable clamping tool, into electrically tight contact with the end portions of the intermediate wire section 29c.

In the form of the invention shown in Figs. 4 to 9, inclusive, the section 29c constitutes the impedance or resistance for affording the desired bias on the electrode 23a, and by its resistance value, this section 29c may be so related as to attain the desired bias and controlling action.

Where high current flow is desired, the resistor 29c may be made from a material such as carbon to afford a biasing resistance of a value up to or in the order of 1000 ohms.

From the foregoing description it will be evident that the present invention enables the useful life of luminous tube apparatus to be increased by control of the common phenomenon of sputtering, and more specifically it will be evident that the electrical discharge in such apparatus under the present invention is controlled in a simple and expeditious manner such that the objectionable effects of such sputtering are avoided.

It will thus be seen from the foregoing description, considered with the accompanying drawing, that the present invention provides a new and improved luminous tube apparatus having the desirable advantages and characteristics and accomplishing its intended objects, including those hereinbefore pointed out, and others which are inherent in the invention.

We claim:

1. In a cold cathode electrode structure for use in a luminous tube apparatus, a metallic collector electrode of elongated and generally cup-shaped form having an open forward end and a closed rear end, a metallic control electrode physically separate from said collector electrode and supported in surrounding and insulated relation to the open end of said collector electrode and disposed so as to extend a sub-

stantial distance beyond the open end of said collector electrode, a biasing connection extended between said electrodes and including a biasing impedance for maintaining a bias on said control electrode when said electrode structure is in use to concentrate and direct an approaching beam to reduce its cross sectional dispersion as it passes through said control electrode and thereby cause the beam to enter the open end of the collector electrode and strike a substantial distance within the collector electrode, and insulating means closing the annular space between said control electrode and said collector electrode to block rearward discharge of slow secondaries between said electrodes.

2. In a cold cathode electrode structure for use in a luminous tube apparatus, a collector electrode made from a refractory metal to afford an elongated and generally cup-shaped form to afford an open forward end and a closed rear end, a control electrode made from a refractory metal and physically separate from said collector electrode, insulating means supporting said control electrode in surrounding and insulated relation to the open end of said collector electrode with said control electrode disposed so as to extend a substantial distance beyond the open end of said collector electrode, said insulating means being so formed and positioned as to close the space between said electrodes at the rear end of said control electrode so as to prevent rearward discharge of slow secondary electrons rearwardly between said electrodes, and a biasing connection extended between said electrodes and including a biasing impedance for maintaining a bias on said control electrode when said electrode structure is in use to concentrate and direct an approaching beam to reduce its cross sectional dispersion as it passes through said control electrode and thereby cause the beam to enter the open end of the collector electrode and strike a substantial distance within the collector electrode.

3. In a cold cathode luminous tube apparatus, an elongated glass tube having an ionizable gas sealed therein, electrode structures disposed within said tube at opposite ends thereof, and at least one of said electrode structures comprising a metallic collector electrode of elongated and generally cup-shaped form having an open forward end and a closed rear end, a metallic control electrode physically separate from said collector electrode and supported in surrounding and insulated relation to the open end of said collector electrode and disposed so as to extend a substantial distance beyond the open end of said collector electrode, a biasing connection extended between said electrodes and including a biasing impedance for maintaining a bias on said control electrode to concentrate and direct an approaching beam to reduce its cross sectional dispersion as it passes through said control electrode and thereby cause the beam to enter the open end of the collector electrode and strike a substantial distance within the collector electrode, and insulating means closing the annular space between said control electrode and said collector electrode to block rearward discharge of slow secondaries between said electrodes.

4. In a cold cathode luminous tube apparatus, an elongated glass tube having an ionizable gas sealed therein, electrode structures disposed within said tube at opposite ends thereof, and at least one of said electrode structures comprising a collector electrode formed from a refractory

metal and of elongated and generally cup-shaped form having a closed rear end and an open forward end, a control electrode formed from a refractory metal and separate from said collector electrode, means supporting said control electrode in surrounding and insulated relation to the open end of said collector electrode and with said control electrode disposed so as to extend a substantial distance beyond the open end of said collector electrode, a biasing connection extended between said electrodes and including a biasing impedance for maintaining a bias on said control electrode when said electrode structure is in use to concentrate and direct an approaching beam to reduce its cross sectional dispersion 15 as it passes through said control electrode and thereby cause the beam to enter the open end of the collector electrode and strike a substantial distance within the collector electrode, and insulating means closing the annular space between said control electrode and said collector electrode to block rearward discharge of slow secondaries between said electrodes.
